UNITED STATES PATENT OFFICE.

CHARLES F. SMITH, OF NEW BRITAIN, CONNECTICUT, ASSIGNOR TO LANDERS, FRARY & CLARK, OF NEW BRITAIN, CONNECTICUT.

DESIGN FOR A KNIFE-HANDLE.

SPECIFICATION forming part of Design No. 35,827, dated March 25, 1902.

Application filed December 21, 1901. Serial No. 86,859. Term of patent 7 years.

To all whom it may concern:

Be it known that I, CHARLES F. SMITH, a citizen of the United States, residing at New Britain, in the county of Hartford and State of Connecticut, have invented and produced a new and original Design for a Knife-Handle, of which the following is a specification, reference being had to the accompanying drawings, forming part thereof.

Figure 1 is a side elevation of a knife-handle, showing my design. Fig. 2 is a plan view of the same.

As shown in the drawings, there is a band 3 at each end of the body 4 of the handle, the said bands being ornamented by flowers 5 and

leaflets 6 in relief and merging together, so as to encircle the middle portion of the said bands, all as shown. The body of the handle is of an ordinary design not peculiar to the end portions, although it harmonizes therewith.

Having described my invention, what I claim as new, and desire to secure by Letters Patent, is—

The design for a knife-handle herein shown and described.

CHARLES F. SMITH.
